UNITED STATES PATENT OFFICE.

RUDOLPH LIEBMANN, OF NEW YORK, N. Y.

DESIGN FOR A BUTTON.

SPECIFICATION forming part of Design No. 18,506, dated August 7, 1888.

Application filed July 6, 1888. Serial No. 279,226. Term of patent 3½ years.

To all whom it may concern:

Be it known that I, RUDOLPH LIEBMANN, a citizen of the United States, residing at New York, in the county and State of New York, 5 have invented and produced a new and original Design for Buttons, of which the following is a specification, reference being had to the accompanying drawing.

My invention consists in a new design for 10 buttons, as fully set forth in the following specification and claim and illustrated in the accompanying drawing, which represents a face view of a button containing my design.

In the drawing, the letter A designates a 15 button having a segmental field, a, completely filled with stars, and a field, b, containing stripes c and d, which are alternately light and dark in color. Said fields a and b are sepa-

rated by a space, e, contrasting in color or shade with said fields. 20

What I claim as new, and desire to secure by Letters Patent, is—

The design for a button, consisting of the field a, completely filled with stars, the field b, containing the stripes c and d, alternately light 25 and dark in color, and the space e, separating said fields, substantially as shown and described.

In testimony whereof I have hereunto set my hand and seal in the presence of two subscribing witnesses. 30

RUDOLPH LIEBMANN. [L. S.]
